COMBINATION PADLOCK

Edward M. Stolarz, Yorktown Heights, N.Y., assignor to
Presto Lock Company, Division of Walter Kidde &
Company, Inc., Elmwood Park, N.J.

Filed Jan. 30, 1976, Ser. No. 653,721

Term of patent 14 years

Int. Cl. D8—07

U.S. Cl. D8—114

FIG. 1

FIG. 2

FIG. 3

FIG. 4

FIG. 5

FIG. 1 is a top plan view of a combination padlock embodying my new design;

FIG. 2 is a right side elevational view, the left side being a mirror image thereof;

FIG. 3 is a bottom elevational view;

FIG. 4 is a top elevational view; and

FIG. 5 is a plan view of the underside of the combination padlock.

I claim:

The ornamental design for a combination padlock, as shown and described.
